SOUND RECORDING AND REPRODUCING SYSTEM

Filed May 14, 1927

Fig. 1.

UNITED STATES PATENT OFFICE

STANLEY S. A. WATKINS, OF RYE, NEW YORK, ASSIGNOR, BY MESNE ASSIGNMENTS, TO ELECTRICAL RESEARCH PRODUCTS INC., A CORPORATION OF DELAWARE

SOUND RECORDING AND REPRODUCING SYSTEM

Application filed May 14, 1927. Serial No. 191,419.

This invention relates to improvements in the art of recording and reproducing motion pictures and accompanying sounds in synchronism.

5 The invention has for its principal object the provision of methods and means for accurately adjusting the synchronization of associated visual and audible programs during the actual operation of the corresponding recording or reproducing devices.

10 A feature of the invention pertains to a movable phonograph recorder or reproducer arm which is capable of being moved in a plurality of directions in a plane parallel to 15 that of the record blank or disc.

Another feature of the invention is concerned with a novel form of mounting for a reproducer or tone arm for phonograph apparatus.

20 A still further feature relates to a scale for use with a phonograph recorder or reproducer, together with an associated movable stylus-carrying arm said scale being marked in appropriate divisions for accurately locating the stylus at any desired point on the record blank or disc.

An additional feature of the invention has to do with a synchronized picture and sound system wherein the phonograph reproducer 30 is invariably driven at a fixed rate of speed with relation to an associated picture projector and with the means for varying the relation between the visual and audible reproductions without disturbing the driving rates of the phonograph and projector.

Other features and advantages of the invention not specifically enumerated, will become apparent after a consideration of the descriptions hereinbelow and after a perusal 40 of the appended claims.

The inventive concept in its broad aspect is not confined to the particular system or apparatus disclosed herein but is susceptible of varied uses in other sound recording and reproducing systems as will be apparent to those familiar with the art and apparatus to which the invention relates. However, for the purpose of enabling a clear understanding to be attained of one particular mode of utilizing the invention, the same will be

shown and described in connection with a synchronized sound and motion picture reproducing system using mechanical media phonograph apparatus, of known construction, and standard motion picture projection apparatus.

In the accompanying drawings:

Fig. 1 represents a side view of a phonograph reproducer embodying the invention, as well as a schematically represented picture projector to be operated in synchronism with the phonograph.

Fig. 2 represents a plan view of the apparatus shown in Fig. 1 together with a lamp indicator, it being understood that the representation of the phonograph apparatus in this figure is essentially diagrammatic.

In the preferred embodiment of the invention as illustrated in the drawings, 1 designates the supporting base or floor for the phonograph and projector equipment and 2 designates bearing pieces securely fastened in the floor 1, and spaced at the proper intervals to correspond with the legs 3 of the telescoping tripod 4. Each of the tripod legs carries an 70 adjusting screw 5 by means of which the phonograph apparatus may be properly leveled. The main supporting column 6 is in the form of a cylinder and telescopes within the annular portion of the supporting tripod. The height of the column 6 may be adjusted 75 and fixed by means of the screws 7. The upper end of the column 6 is hollow and carries suitable bearings 8 in which turntable shaft 10 is suitably journaled. Shaft 10 carries at its lower end a suitable gear 11. Preferably between the upper and lower sections of the shaft 10 there is provided a mechanical filter schematically represented by the rectangle 12 for the purpose of preventing the 80 transmission of "gear noises" to the turntable.

90 95 100 Co-operating with the gear 11 is the worm 14 fixed to shaft 15 which is mounted in suitable bearings in the gear box 13. 16 represents a driving motor with which is associated suitable regulating mechanism for maintaining the motor speed independent of variations in the supply circuit. The motor driving shaft is preferably coupled to the shaft 15 through the flexible coupling 17 which may

be designed to prevent the transmission of vibrations from the motor to the turntable. Motor 16 is mounted upon a supporting table having legs 18 which telescope with corresponding hollow cylindrical supports 19 fastened to the floor. The height of the motor table may be adjusted and fixed by means of the screws 20. Motor 16 also drives the shaft 21 carrying the gear 22 which operates with gear 23 for driving shaft 26. Shaft 26 is preferably coupled to the gears 23 and 27 by means of universal joints schematically represented by the rectangles 24 and 25. The main driving shaft 29 for the picture projector 30 carries the gear 28 which co-operates with the gear 27.

38 represents a wax disc on which is incorporating a record of the sound program to be reproduced, this record being preferably in the form of continuous spirally arranged wave-like cuttings in the body of the disc, the variations in the sounds being preferably represented by corresponding varying amplitudes of the wave-like cuttings. For the purpose of translating these varying cuttings into corresponding electric currents any well known form of electromechanical reproducer 45 may be employed. This reproducer is adapted to be actuated by the stylus 37 which follows the record groove in the disc, and is mounted in any suitable manner on the arm 36 which is pivoted for movement in a vertical plane in the bifurcated extensions 71 and 72 of the pin 73. Pin 73 is provided with a bearing shoulder 46 which serves as a support for the left hand end of the arm 36. Pin 73 fits snugly in a recess in the arm 35 thus allowing arm 36 to be moved in both horizontal and vertical planes without disturbing the position of arm 35 which itself is capable of rotation about the main column 6. For this latter purpose the right hand end of arm 35 terminates in an annular portion 74 which embraces the column, the height of arm 35 being capable of adjustment by means of the rings 31, 32 and the screws 33. Because of the size of arm 35 as compared with arm 36, the latter is free to move in a horizontal plane, as a result of the stylus following the sound groove, without moving the arm 35. It will be noted, however, that movement of the arm 35 manually by an attendant causes the reproducer arm 36 to be moved bodily with respect to the record disc. For example, as shown in Fig. 2, the reproducer arm 36 (as shown in dotted lines) is illustrated as having been rotated manually through an angle A. It will also be noted that this bodily movement of the arms 35 and 36 may be effected while the disc 38 is rotating, thus in effect causing a shortening or lengthening of the record depending upon whether the arm 35 is rotated clockwise or counterclockwise.

For the purpose of accurately gauging the degree to which the arm 35 is to be moved,

a graduated scale plate 47 is provided, this plate being affixed to the main supporting column 6 in the manner shown in Fig. 1 and directly beneath the turntable. With the scale mounted as shown, each of the markings thereon corresponds to a segmental portion of the record disc. Inasmuch as the disc 38 is rotated at a constant speed each segment of the sound record therefore corresponds to a certain length of the moving picture film passing through the projector 30. If desired, the divisional marks on the scale 47 may be calibrated to read directly in "picture frames" in which case the attendant may accurately lengthen or shorten the sound reproduction with respect to the visual reproduction simply by turning the arm 35 in a clockwise or a counter-clockwise direction.

In some cases it may be desirable for the operator to note at any instance the relative position of the reproducer with respect to the record disc without his being able to closely inspect the scale 47. For this purpose the scale which is preferably of non-conducting material is provided with contact studs 48 at each of the main divisions of the scale. As shown in Fig. 1 these contact studs protrude from the upper surface of the scale plate and are adapted to be contacted with the brush 49 which may also serve as a pointer for locating the position of the reproducer. This brush as shown is connected by means of the conductor 51 to one pole of the battery 52, the other pole being connected to the common terminals of the lamps 56, 57, etc. The remaining terminals of the lamps are connected to corresponding contact studs on the plate 47 as shown in Fig. 2. The series of lamps 56, 57 are all preferably of a different color from lamps 59, 60, etc., so that the attendant may note at a glance how many "frames" the sound reproduction is in advance of, or behind, the picture projection.

When it is desired to produce a synchronized sound and picture program the wax disc containing the sound record is placed upon the turntable 9 with the reproducer stylus 37 opposite to an appropriate starting mark on the disc. At the same time the corresponding picture film to be projected is inserted in the machine 30 with the "starting frame" in alignment with the optical system of the projector. In some cases it may be known beforehand that the picture film is slightly longer than the corresponding sound record. For example, from previous "runs" it may be observed that the picture finishes about five frames before the sound record is concluded, this discrepancy not being particularly noticeable to the ordinary auditor. To compensate for this difference the operator prior to starting the motor 16 turns the arm 35 in a clockwise direction from the zero position to a position where the brush 49 contacts with the stud 58. This

movement of the arm 35 and consequently the reproducer arm 36 is in effect a lengthening of the sound record. In other cases the attendant may observe during the operation of the phonograph and projector that at some particular point the picture appears to be behind the sound reproduction in which case the arm 35 may be rotated in a counter-clockwise direction to the point where the attendant notes that the sound and visual reproductions are in exact phase. Thus accurate phase relations may be secured between the projected picture and the accompanying sound without interrupting the operation of either the phonograph or the projector.

While in the foregoing description the invention has been described in connection with a particular type of sound and picture projecting system, it is to be understood that the invention is of use in other types of systems. For example instead of employing a single motor for driving both the sound and picture reproducers, separate motors may be employed utilizing electrical or other well known synchronizing arrangements. Similarly while a particular form of phonograph is disclosed it will be apparent that the invention is applicable to other forms of sound reproducing instruments, for example, those employing photographic records, it being understood that the invention in its broad aspects pertains to the idea of varying the effective synchronism without disturbing the operation of either the phonograph or picture machines.

What I claim is:

1. In a synchronized sound and picture system, a phonographic sound record disc, means for moving said disc, a motion picture machine having driving means adapted to be operated in constant synchronism with the disc moving means, means controlled by said disc for reproducing a sound program, rotative means for changing the effective length of the reproduced sound program without disturbing the synchronism between said driving means and the disc moving means, and lamp signals controlled by said rotative means for indicating to an attendant the amount to which the effective length of the sound program is varied.

2. In a synchronized sound and picture reproducing system, a phonographic sound record disc, a motion picture machine, means for rotating said disc and operating said machine in continuous synchronism, means operated by said disc for reproducing a sound program, rotative means for varying the effective length of the reproduced program without disturbing the synchronism between the rotating disc and the operation of said machine, a series of lamps for indicating the amount to which the reproduced sound program is shortened, and another series of lamps for indicating the amount to which the reproduced

sound program is lengthened, both said series of lamps being controlled by said rotative means.

3. In combination a phonograph turn-table, a wax disc mounted thereon and containing a continuous cutting constituting a record of a sound program, means comprising a stylus controlled by said cutting for reproducing said program, a motion picture machine, a moving picture film adapted to be fed through said machine, motor means for driving said turn-table and said picture machine, and means for moving said stylus longitudinally in said cutting to vary the effective length of the reproduced sound program. 70 75 80

4. In combination a phonograph turn-table, a wax disc mounted thereon and containing a continuous cutting constituting a record of a sound program, means comprising a stylus controlled by said cutting for reproducing said program, a motion picture machine, a moving picture film adapted to be fed through said machine, motor means for driving said turn-table and said picture machine, and means for temporarily varying the 85 tempo of the sound program as recorded on said disc while maintaining constant speed of both the turntable and the picture machine. 90

5. In combination a phonograph turn-table, a stylus bearing arm cooperating therewith, a mounting for said arm capable of horizontal circular movement independently of the movement of said arm, a motion picture machine, a moving picture film adapted to be fed through said machine, motor means 95 for driving said turn-table and said picture machine, and means including said movable mounting for varying the effective synchronism between the sound program and the picture program without varying the speed 100 105 of either the turn-table or picture machine.

6. In combination, a motion picture machine, a moving picture film adapted to be fed through said machine, a phonograph turntable, motor means for driving said turn-table and said picture machine, a stylus and an arm therefor cooperating with said turn-table, a pivotal joint for said arm to render it capable of movement in both horizontal and vertical planes, a support for said arm, 110 115 said support being rotatable about the axis of said turntable to vary the relative position of said stylus with respect to said turntable.

7. In combination, a phonograph turn-table, a phonograph sound record disc, a 120 stylus bearing arm cooperating therewith, a pivotal joint for said arm to render it capable of movement in both horizontal and vertical planes, a mounting for said arm, a motion picture machine, a moving picture film adapted to be fed through said machine, motor means for driving said turntable and said picture machine, and means including said mounting whereby said stylus arm is moved bodily over the surface of the record 125 130

independent of the vertical and horizontal movements of said arm for varying the effective synchronism between the sound program and the picture program while maintaining constant the speed of both the turntable and the picture machine.

8. In combination, a phonograph turntable, a stylus bearing arm cooperating therewith, a rotatable mounting for said arm, a motion picture machine, a moving picture film adapted to be fed through said machine, motor means for driving said turntable and said picture machine at a predetermined speed and means cooperating with said mounting for indicating the distance in picture frames through which the stylus arm is rotated.

In testimony whereof, STANLEY S. A. WATKINS has signed his name to this specification this 10th day of May, 1927.

STANLEY S. A. WATKINS.
